UNITED STATES PATENT OFFICE

JAMES L. PAXTON, OF OMAHA, NEBRASKA.

AIR-COOLED SWAB-CUP.

1,245,764.

Specification of Letters Patent.

Patented Nov. 6, 1917.

Application filed April 10, 1916. Serial No. 90,217.

To all whom it may concern:

Be it known that I, JAMES L. PAXTON, a citizen of the United States, residing at Omaha, in the county of Douglas and State 5 of Nebraska, have invented certain new and useful Improvements in Air-Cooled Swab-Cups; and I do hereby declare the following to be a full, clear, and exact description of the invention, such as will enable others 10 skilled in the art to which it appertains to make and use the same.

This invention relates to improvements in lubricating apparatus, and more particularly to swab retaining devices for piston 15 rods.

The object in view is the avoidance of injury to the swab incident to excessive heat, as, for instance, such as results from the employment of superheated steam in 20 the actuation of the piston.

A further object in view is the cooling of the swab and its retainer automatically by the aid of air circulation.

With these and further objects in view, 25 as will in part hereinafter become apparent and in part be stated, the invention comprises certain novel constructions, combinations and arrangements of parts as subsequently specified and claimed.

30 In the accompanying drawing:—

Figure 1 is a vertical section taken along the plane of the axis of a swab retainer embodying the features of the present invention, a fragment of the gland and a fragment 35 of the piston rod being seen.

Fig. 2 is a transverse axial section taken on the plane indicated by line 2, 2 of Fig. 1.

Fig. 3 is a front end view of the retainer, showing the piston rod in section.

40 Referring to the drawing by numerals, 1 indicates a piston rod of an engine, such, for instance, as a reciprocating steam engine. 2 is the usual packing gland surrounding the piston rod and engaging the

45 cylinder head not shown. It has been common heretofore to connect a cup or casing directly to the outer end of the packing gland and surrounding the piston rod for containing a swab arranged to engage the piston rod and to deliver lubricant thereto.

50 However, much difficulty has been experienced with such swabs when superheated steam is employed, since the heat is sufficient to char the swab and thus not only 55 destroy its efficiency but actually render its use injurious.

To overcome the difficulty thus arising, an air cooling swab container or casing 3 is provided and arranged to surround the piston rod 1, the casing being formed with 60 an internal annular swab containing space in which is arranged the swab 4. Air cooling flanges 5 outstand axially from the casing 3, so as to aid in distributing heat from the casing to the atmosphere. 65

The casing 3 is spaced from the outer end of the gland 2 so as to leave an air space 6. This space is bridged at various points. A cap 7 is so arranged as to shed any cinders or foreign matter falling toward the piston 70 rod 1 without at the same time interfering with the free circulation of air about the piston rod between the outer end of gland 2 and the inner face of casing 3. Cap 7 forms one of the bridging elements, and 75 others consist of studs 7 and bases 7". These several bridging elements are preferably formed integral with the casing 3, but may be otherwise attached thereto.

A cup 8 is arranged at the upper portion 80 of casing 1 and communicates through a port 9 with the interior of the casing so as to afford means for facilitating the supply of lubricant to the swab 4. Cup 8 is adapted to be filled with waste retained in position by wires 8', the waste preventing spilling of contained oil while allowing drainage thereof through aperture 9. The casing 3 is anchored in place by bolts 10, 10, extending through flanges 11, 11, formed on 90 the casing 3, said bolts being threaded into appropriate portions of the gland 2 or directly into the cylinder head.

A very important advantage of the present invention resides in the fact that it prevents pieces of swabbing from being drawn by suction from the cylinders into the packing and injuring or destroying it. 95

What I claim is:—

1. The combination, with a piston rod and 100 a packing gland, of a swab container disposed to retain a swab in contact with the piston rod and having heat dissipating fins on one side and spacers on its other side to engage the packing gland for enabling access of air between the gland and container. 105

2. The combination, with a piston rod and a packing gland, of a swab container disposed to retain a swab in contact with the 110 piston rod, the said container being constructed and arranged to be air cooled and

- located for enabling access of air between the gland and container, and means bridging the space between the gland and container and including a cap element adapted 5 to overhang the piston rod for preventing access of cinders to the piston rod.
3. The combination, with a piston rod and a packing gland, of a swab container disposed to retain a swab in contact with the 10 piston rod, the said container being constructed and arranged to be air cooled and located for enabling access of air between the gland and container, and means bridging the space between the gland and container for preventing access of cinders to the piston rod, the said bridging means being formed of sections for permitting free circulation of air.
4. A swab container for piston rods comprising a container casing, and means extending therefrom adapted to space the casing from contiguous engine parts when the casing is operatively located relative to a piston rod, the said spacing means being 20 formed to provide a protecting bridge preventing access of foreign matter to the piston rod between the casing and the contiguous engine part.
5. A swab container for piston rods comprising a casing adapted to sustain a swab 30

in engagement with a piston rod, and air cooling means coöperating with the casing for effecting distribution of heat therefrom to the atmosphere.

6. A swab container for piston rods comprising 35 a casing adapted to sustain a swab in engagement with a piston rod, and air cooling flanges outstanding from the casing.

7. A swab container for piston rods comprising 40 a casing adapted to surround a piston rod and having an internal annular space adapted to receive a swab, and having exterior cooling flanges to aid in the distribution of heat from the casing.

8. A swab container comprising a casing 45 adapted to be secured to a packing gland about a piston rod and provided with an internal annular space to receive a swab for contact with the piston rod, and spacers arranged to lie between the packing gland and the casing when the latter is in place and being spaced apart to provide air passages between the gland and the casing to cool the latter.

In testimony whereof I affix my signature 50 in presence of two witnesses.

JAMES L. PAXTON.
